UNITED STATES PATENT OFFICE.

JOSEPH LUCCINO, OF NEW YORK, N. Y., ASSIGNOR TO MANHATTAN DIVANETTE CO., OF BROOKLYN, NEW YORK, A CORPORATION OF NEW YORK.

CONVERTIBLE BED AND DIVAN OR SOFA.

1,139,785.

Specification of Letters Patent. Patented May 18, 1915.

Application filed May 29, 1914. Serial No. 841,830.

To all whom it may concern:

Be it known that I, JOSEPH LUCCINO, a citizen of the United States, and a resident of the city of New York, borough of Brooklyn, in the county of Kings and State of New York, have invented a new and Improved Convertible Bed and Divan or Sofa, of which the following is a full, clear, and exact description.

10 The object of the invention is to provide a new and improved convertible bed and divan or sofa, arranged to permit the user to swing the sections into extended position to form a double bed or into a folded position to provide a divan or sofa, the converting of the bed into a divan or sofa and vice versa requiring very little physical exertion on the part of the operator.

In order to accomplish the desired result 20 use is made of a stationary main frame and a bed spring formed in sections, of which one is the head section, another is the middle section and is pivotally connected with the head section, and a third one is the foot section pivotally connected by connecting links 25 with the middle section, parallel bars fulcrumed on the main frame, and of which the rear bar is pivotally connected with the joint of the head section and the middle section, and the forward bar is pivotally connected 30 with the middle section at a point between the ends thereof, and a link connecting the said head section with the said connecting links to permit of readily folding 35 the several sections within the main frame to form a divan or a sofa, or to allow of extending the sections to provide a double bed.

A practical embodiment of the invention 40 is represented in the accompanying drawings forming a part of this specification, in which similar characters of reference indicate corresponding parts in all the views.

Figure 1 is a side elevation of the convertible bed and divan or sofa, with the sections in extended position to form a bed, and with the main frame shown in section and a portion of the link broken out; Fig. 2 is a like view of the same with the sections in partly folded position; Fig. 3 is a similar 45 view of the same with the sections in folded position to form a divan or a sofa; and Fig. 4 is a plan view of the convertible bed and divan or sofa with the sections in extended position, and the head section shown in section 50 on the line 4—4 of Fig. 1.

The convertible bed and divan or sofa consists essentially of a stationary main frame A and a sectional bed spring formed in sections B, C and D, of which the section B is the head section, the section C is the middle section, and the section D is the foot section and is provided at its outer end with fixed legs E. The foot section D is connected to the middle section C by connecting links F, and the middle section C is pivotally connected by pivots G to the head section B, and the said pivots G are also engaged by the upper ends of bars H fulcrumed at their lower ends on the sides of the main frame A. A second bar H' parallel to the bars H and located in front thereof is pivoted at its lower end to the sides of the main frame A, and is pivotally connected by a pivot G' with the middle section C at a point between the ends thereof. The head section B is provided at its forward end with slightly downwardly curved extensions B' pivotally connected by links I with the connecting links F at the middle thereof.

The outer end of the middle section C is provided with legs J pivotally connected near their upper ends by links K with extensions H² formed on the upper ends of the forward bars H'. The forward bars H' are pivotally connected near their upper ends by links L with the head section B in the rear of the pivots G to assist in supporting the head section B in horizontal position and also to assist in moving the head section B into vertical position when folding the sections as shown in Fig. 3.

By the arrangement described, the sections B, C and D and the links F are adapted to extend in a horizontal position to form a bed, the sections being properly supported by the bars H, H' and the legs J and E. By the arrangement described the sections can be moved into folded position so that the head section B extends vertically within the main frame A while the middle section C and the end section D are disposed horizontally in the frame A, one above the other, and spaced apart by the connecting links F which now stand in vertical position, as will be readily understood by reference to Fig. 3.

In order to insure an easy movement of the sections when extending or folding the same, use is made of counterbalancing springs N attached to the brackets A' ar-

ranged in the lower portion of the main frame A, the springs extending upwardly and inwardly and connected with a cross piece C' of approximately U shape, thus standing at an angle to the plane of the section C. The parts are so located that when the sections are in the partly folded position shown in Fig. 2 the springs N are disposed vertically, and on swinging the sections into the frame A the springs N are placed under tension, and in a like manner when the sections are moved from this intermediate position shown in Fig. 2 into an extended position then the springs are likewise placed under tension, as will be readily understood by reference to Fig. 1. Thus when the sections are moved from the extended position into the folded position the springs L aid the operator, and in a like manner when the sections are moved from folded position into extended position the springs aid the operator so that very little physical exertion is required on the part of the operator to extend or to fold the sections.

The head section B is provided with an upholstered swing back O pivotally connected at its upper end with slides P mounted to slide up and down in guideways P' secured to or formed on the sides of the main frame A. The under side of the back O is provided with runners O' terminating at their forward ends in beveled portions O², and the said runners are adapted to be engaged by friction rollers Q, Q' spaced apart and journaled in brackets Q² attached to the head section B. The rear ends of the runners O' terminate in shoulders O³ on which are seated the friction rollers Q at the time the parts are in folded position, as shown in Fig. 3. Now when the sections are moved into extended position and a swinging motion is given to the head section B in a forward and upward direction then the friction roller Q imparts an upward swinging motion to the back O until the parts reach the position shown in Fig. 2, and then on further extension of the sections the head section B is caused to swing downward and rearward so that the friction roller Q leaves the runner O' and the other friction roller Q' engages the beveled end O² to support the back O in a slightly forwardly and downwardly inclined position, as plainly indicated in Fig. 1. By providing the slides P, the back O is not liable to bind during its up and down swinging movement thus easing the opening and closing of the sections.

An upholstered seat R is provided at its forward end with a footboard R' provided with brackets S having elongated openings S' through which extends a transverse bar F' connecting the two links F rigidly with each other and being approximately U shape. The rear end of the seat R is pro-

vided with bolts T slidably engaging lengthwise extending slots D' formed in the foot section D near the outer end thereof. By the arrangement described the seat R hangs downward from the connecting bar F' of the links F and the foot section D, and when the operator swings the foot section D upward then the under side of this section D finally comes in contact with the under side of the seat R so that the foot section D and the seat R move together to final position, that is, the upholstered seat R finally reaches a top position on the seat R, as shown in Figs. 2 and 3, and moves down with the foot section D into final position within the frame A. By reference to Fig. 3 it will be noticed that the seat R reaches lowermost position prior to the back O reaching its lowermost position so that the lower end of the back O rests on the top of the rear end of the seat R thus making a fine joint between the seat R and the back O.

The bottom cross bar D² of the foot section D is slightly extended beyond the side rails of the said section D to rest on the links L when the sections are moved into folded position, as shown in Figs. 2 and 3.

The operation is as follows: Presuming that the sections are in extended position, as shown in Figs. 1 and 4, and it is desired to fold the sections, the operator takes hold of the end cross bar D² of the foot section D and swings the latter up. In doing so the foot section turns on the links F as the fulcrum, and when the foot section reaches a vertical position the under side of the seat R rests on the under side of the section D, the seat R swinging on the cross bar F' as a fulcrum during said movement. A further swinging motion given to the foot section D toward the main frame A now causes the links F to swing on the middle section C and when this takes place the links I impart an upward swinging motion to the head section B. The operator while swinging the foot section D and seat R downward also pushes on the seat R so that the parallel bars H, H' begin to swing upward and in doing so the middle section C together with the links F, the foot section D and the seat R are raised and the back O is swung upward by the action of the head section B caused to swing upward by the links I. When the foot section D and the seat R reach a horizontal position, the projecting ends of the cross bar D² rest on the links L, thus limiting further downward swinging motion of the said foot section D and its seat R. The upward swinging motion of the parallel bars H and H' is aided by the springs N. During the upward swinging motion of the parallel bars H, H' the links K impart an upward swinging motion to the legs J of the middle section C. The operator on further exerting a push on the seat R causes

the parallel bars H, H' to swing downward into the final folding position shown in Fig. 3, thus carrying along the middle section C, the foot section D and seat R. During this 5 downward movement the springs N are again placed under tension to insure an easy folding motion, and the head section B is caused to move downward and rearward thus, allowing the back O to swing downward to final position.

10 It will be noticed that during the time the back is held raised the fixed legs E can readily pass under the back into the rear portion of the main frame A, and the rear 15 end of the seat R passes slightly rearward of the lower end of the back O so that the said lower end rests on top of the rear portion of the seat R, as plainly shown in Fig. 3.

20 It will further be noticed that the middle section C and the foot section D when in folded position are spaced apart to accommodate the middle and foot sections of a mattress, and the cross bar D² is spaced 25 from the head section B to accommodate the head section of the mattress.

When it is desired to extend the sections with a view to form a bed, the operator 30 takes hold of the footboard R' of the seat R and exerts an upward and forward pull so that the parallel bars H, H' swing upward, this movement being aided by the springs N. During this upward movement the sections 35 B, C and D and the back O assume the position shown in Fig. 2. The operator now takes hold of the cross bar D² and imparts successively an upward and forwardly 40 downward swinging motion to the foot section D and at the same time exerts a slight forward pull so that the sections move finally into the extended position shown in Fig. 1. The back O during the final return movement is held in an inclined position by the roller Q' to form an abutment for the 45 pillows.

From the foregoing it will be seen that the sections B, C, and D can be readily extended to form a bed, the seat R being held under the foot section D and being thus completely 50 out of the way while the back O is utilized as an abutment for the pillows. When the sections are in folded position the seat R and the back O are firmly supported within the frame A to allow proper use of the divan 55 or sofa.

Having thus described my invention, I claim as new and desire to secure by Letters Patent:

1. A convertible bed and divan, comprising a stationary main frame, a head section, a middle section pivotally connected with the said head section, a foot section, a connecting link pivotally connecting the middle section with the said foot section, parallel 60 bars fulcrumed on the said main frame, and 65

of which the rear bar is pivotally connected with the joint of the head section and middle section, and the forward bar is pivotally connected with the middle section at a point between the ends, and a link connecting the 70 said head section with the said connecting link.

2. A convertible bed and divan, comprising a stationary main frame, a head section, a middle section pivotally connected with 75 the said head section, a foot section, a connecting link pivotally connecting the said middle section with the said foot section, parallel bars fulcrumed on the said main frame and of which the rear bar is pivotally 80 connected with the joint of the head section and middle section, and the forward bar is pivotally connected with the middle section at a point between the ends, a link connecting the said head section with the said connecting link, and a link connecting the forward bar with the said head section.

3. A convertible bed and divan, comprising a stationary main frame, a head section, a middle section pivotally connected with 90 the said head section, a foot section, a connecting link pivotally connecting the said middle section with the said foot section, parallel bars fulcrumed on the said main frame, and of which the rear bar is pivotally 95 connected with the joint of the head section and middle section and the forward bar is pivotally connected with the middle section at a point between the ends, a link connecting the said head section with the said connecting link, a leg pivoted on the outer end of the middle section, and a link connecting the said leg with an extension on the upper end of the said forward bar.

4. A convertible bed and divan, comprising 105 a stationary main frame, a head section, a middle section pivotally connected with the said head section, a foot section, a connecting link pivotally connecting the said middle section with the said foot section, parallel bars fulcrumed on the said main frame and of which the rear bar is pivotally 110 connected with the joint of the head section and middle section and the forward bar is pivotally connected with the middle section 115 at a point between the ends, the said head section having a forward extension, and a link pivotally connecting the head section extension with the said connecting link at a point between the ends of the said connecting link.

5. A convertible bed and divan, comprising 120 a stationary main frame, a head section, a middle section pivotally connected with the said head section, a foot section, connecting links pivotally connecting the said middle section with the said foot section, an angular bar connecting the said links, parallel bars fulcrumed on the said main frame, and of which the rear bar is pivotally con- 125 130

neected with the joint of the head section and middle section and the forward bar is pivotally connected with the middle section at a point between the ends, links connecting 5 the said head section with the said connecting links, a divan back, and a slide on the upper end of the said main frame and to the upper end of which the upper end of the 10 said divan back is pivoted, the lower end of said back being engaged by the said head section.

6. A convertible bed and divan, comprising a stationary main frame, a head section, a middle section pivotally connected with 15 the said head section, a foot section, connecting links pivotally connecting the said middle section with the said foot section, an angular bar connecting the said links, parallel bars fulcrumed on the said main frame 20 and of which the rear bar is pivotally connected with the joint of the head section and middle section and the forward bar is pivotally connected with the middle section at a point between the ends, links connecting 25 the said head section with the said connecting links, and a seat hung on the said foot section and the said angular bar.

7. A convertible bed and divan, comprising a main frame, a head section having a 30 forward extension, a middle section pivotally connected with the said head section, a foot section, connecting links connecting the said middle and foot sections with each other, parallel bars fulcrumed on the said 35 main frame and of which the rear bar is pivotally connected with the joint of the head and middle sections and the forward bar is pivotally connected with the said middle section and is provided with an 40 upward extension, a link connecting the extension of the head section with the middle of the said connecting link, a link connecting the said forward bar with the said head section, a leg on the forward end of 45 the middle section, and a link connecting the said forward bar extension with the said leg.

8. A convertible bed and divan provided with a stationary main frame, a divan back, 50 a slide mounted to slide up and down on the said main frame and to the upper end of which the upper end of the said back is pivoted, and a head section having a swinging motion and provided with an extension engaging the said back to impart 55 a swinging and a sliding motion to the said back.

9. A convertible bed and divan provided

with a head section, a middle section pivotally connected with the head section, a foot 60 section, connecting links connecting the middle section with the said foot section and provided between their ends with an angular cross bar, parallel bars pivotally connected with the said head and middle 65 sections, a link connecting one of the said parallel bars with the said connecting links at the said cross bar, a leg fixed on the outer end of the said foot section, and a divan seat having a slidable connection at 70 one end with the said cross bar and having its other end slidably connected with the said foot section.

10. A convertible bed and divan provided with a head section, a middle section 75 pivotally connected with the head section, a foot section, connecting links connecting the middle section with the said foot section and provided between their ends with an angular cross bar, parallel bars pivotally connected with the said head and middle 80 sections, a link connecting one of the said parallel bars with the said connecting links at the said cross bar, a leg fixed on the outer end of the said foot section, a 85 divan seat having a slidable connection at one end with the said cross bar and having its other end slidably connected with the said foot section, and a counterbalancing 90 spring attached to the main frame between the parallel bars and connected with the said middle section.

11. A convertible bed and divan, comprising a main frame having a swing back, a head section controlling the said swing 95 back, a middle section pivotally connected with the said head section and provided with pivoted legs, a foot section having fixed legs, connecting links connecting the middle section with the said foot section, 100 a seat hung on the said connecting links and the said foot section, means controlling the folding and extending of the said sections, and means for operating the pivoted legs of the middle section as the sections are folded or extended, said last 105 named means including bars pivotally connected to the frame and to the middle section.

In testimony whereof I have signed my 110 name to this specification in the presence of two subscribing witnesses.

JOSEPH LUPPINO.
